DEVICE FOR TENSIONING BUNDLING STRAPS
Daniel P. Schweste, East Orange, and Francis A. O'Loughlin, Scotch Plains, N.J., assignors to The Thomas & Beits Co., Elizabeth, N.J., a corporation of New Jersey

Filed June 12, 1962, Ser. No. 202,013
7 Claims. (Cl. 140—123.6)

The present application is an improvement over the structure disclosed in U.S. Patent No. 3,047,945, issued August 7, 1963.

The invention relates to devices for tensioning and locking tie straps or the like and more particularly to an improved hand tool adapted for tensioning a flexible plastic strap after it has been looped about a plurality of articles disposed in bunched parallelism, and for thereafter maintaining the strap under tension while the tool is manipulated to lock or otherwise secure the strap upon itself against reverse movement, the tool being subsequently actuated toward closed position to perform a severing operation on the extended free end portion of the strap.

More specifically, the invention resides in the herein described improvements in a hand tool of the parallel action pliers type, shown in the above Patent No. 3,047,945, which is particularly adapted for tensioning locking and severing individual flexible plastic bundling straps of the character disclosed in U.S. Patent 3,002,557, whereby the application of such straps on a plurality of bunched insulated electric conductors, for example, may be effected at spaced points therealong with greater convenience and dispatch and, with all tied straps under equal tension.

Heretofore, in tieing such bundling straps with the hand tool shown in the above Patent No. 3,047,945, it was necessary to bring the strap manipulating plate elements, on the jaws thereof, into a predetermined overlapping position, relative to the engaged body portion of the strap, solely by the operator's skill or practice with the tool, and so hold the tool while turning it through an angle of 90 degrees to bring the engaged body portion of the strap into alignment with a pair of aligned slots extending centrally across the eyelet in the head-end portion thereof for the purpose of securing the strap against reverse movement after being drawn taut about a plurality of bunched electric conductors.

The aforesaid hand tool, however, possessed certain disadvantages in that the repeated movement of the jaw members toward each other to a predetermined position required an unreasonable degree of skill since misjudgment resulted in the premature severance of such straps. Moreover, in the use of the aforesaid tool, the strap passed through the longitudinal center thereof and, in a modified form, pivotal action was such that one side of the jaw members was unobstructed for the sidewise insertion of a strap therebetween.

Accordingly, it is an object of the invention to provide improvements in a hand tool of the character described whereby the above noted disadvantages are obviated.

A further object of the invention is to provide a hand tool of the character described whereby it is possible for an inexperienced operator to tie a large number of bundling straps with greater efficiency and dispatch than was formerly possible with the unimproved hand tool in the hands of an experienced operator.

Another object of the invention is to provide an im-

2

proved hand tool of the character described whereby any number of flexible plastic bundling straps are all placed under a uniform degree of tension in the tieing thereof with said tool.

5 A further object of the invention is to provide an improved hand tool of the forged steel type wherein the integral jaws thereof are off-set at a small angle to the longitudinal center of the tool for the sidewise reception of a plastic bundling strap therebetween.

Another object of the invention is to provide an improved hand tool as described, wherein movement of the jaw members toward each other to a predetermined preset position is controlled automatically by means adapted to be released by an operator to effect a strap severing operation after the same has been secured against reverse movement.

With the above and other objects in view, the invention resides in the novel construction, combination, and arrangement of parts, the novel features of which are set forth with particularity in the appended claims, the invention itself, however, both as to its organization and method of operation, together with additional objects and advantages thereof, being best understood from the following description of a specific embodiment thereof, when taken in connection with the accompanying drawing in which:

FIGURE 1 is a perspective view illustrating the manner in which the improved hand tool is utilized in manipulating a plastic bundling strap into taut position about a plurality of bunched wire conductors and before severing the surplus end portion of the strap from its looped portion.

FIGURE 2 is a fragmentary side elevational view of the improved hand tool with its jaw members in full open position and showing a plastic bundling strap end portion as positioned sidewise therebetween.

FIGURE 3 is a fragmentary sectional view taken on the line 3—3 of FIGURE 2.

FIGURE 4 is a fragmentary side elevational view 40 similar to FIGURE 3, showing the jaw members of the tool after they have been moved toward each other, short of cut-off or closed position, with a free end portion of a bundling strap therebetween.

FIGURE 5 is a fragmentary sectional view taken on the line 5—5 of FIGURE 4.

FIGURE 6 is a view similar to FIGURE 5, showing the jaw members after they have been released for continued movement toward each other to "cut-off" position, from the position shown in FIGURE 4, by moving a detent member, hingedly connected to one jaw member, out of engagement with the other jaw member.

FIGURE 7 is a fragmentary cross-sectional view, taken on the line 7—7 of FIGURE 6.

FIGURE 8 is a fragmentary top plan view of the hand tool, shown in the preceding figures, illustrating the angularly off-set jaw members with respect to the longitudinal center line of the tool, and a portion of a bundling strap disposed between the jaw members at an angle to said longitudinal center line.

60 Referring to the drawing, the invention resides in a hand tool of the pliers type, generally indicated at 10, comprising a pair of crossed handle members 12, of forged steel pivotally connected as at 14, in accordance with the "Pivoted Tool Joint Construction" disclosed in Porter Patent Number 2,920,927, said handle mem-

bers including a pair of jaws 16, of rectangular cross-section formed integral therewith and adapted to swing in an arc in scissors fashion when moved toward each other upon angular manipulation of said handle members. As best shown in FIGURE 2, the jaws 16, and pivoted handle members 12, are yieldably maintained in open or spaced apart position by means of a coiled compression spring 18, disposed between the opposed inner faces of the handle members 12, adjacent the pivotal connection 14, with each of its opposite ends seated in a suitable recess formed in the inner faces of the respective handle members 14, by means of a drill or the like, the hand grip portion of the handle members 12 being provided with a plastic covering or sleeve 20, whereby to insulate a portion of the tool 10 and at the same time provide a non-slip surface thereon.

In accordance with the invention and as best shown in FIGURES 1 and 8, a major portion of the jaws 16, extending beyond the fulcrum or pivotal connection 14, between the handle members 12, is off-set or bent to the left or toward the bottom edge of the sheet, as at 22, in FIGURE 8, and then in the opposite direction, as at 24, to extend at a small angle toward the longitudinal center line 26 through the handle members 12, whereby the jaws 16, are so off-set with respect to said handle members that a bundling strap S may be positioned between the jaws 16, side-wise in angular off-set relation to the pivotal connection 14, as well as longitudinally of the jaws 16, from the nose-end thereof rearwardly in spaced angular relation to the handle members.

Further in accordance with the invention, the lower one of the jaws 16 terminates at its nose-end in an integral right angular extending lip or tooth 25, in opposed relation to the nose-end of the opposite or upper jaw 16, the lip or tooth 25 being slightly tapered and its free end provided with an angular rake or clearance to form a transverse knife edge 28, having a V-notch 30 centrally of its width to provide clearance for the ribbed, arcuate face 32 of the body portion of a strap S and to facilitate cutting thereof when brought into engagement therewith.

The upper or opposite jaw 16 is provided at its nose end with an angle plate 34, having one leg thereof secured on the outer face of the said upper jaw 16 by means of suitable screws 36 or the like, the opposite leg 38 of the angle plate 34 extending across the nose end of the upper jaw 16, at right angles to the opposing faces of the jaws 16, and in partial overlapping sliding contact relation with the lip or tooth 25, when the jaws 16 of the tool 10 are in the position shown in FIGURE 4.

As shown in FIGURES 2 and 3, the extended free leg 38 of the angle plate 34 is provided with a slot 40, extending inwardly from one side margin thereof for the snug reception therein of the body portion of a bundling strap S, whereby the width of the slot 40 is slightly less than the width of the body portion of the strap S, for maintaining the same against lateral as well as reverse movement when extended through the slot 40.

Further in accordance with the invention and as best shown in FIGURE 2, means for drawing a strap S taut about a plurality of bunched parallel linear elements E, in small successive increments of adjustment comprises an arcuate pawl 44, provided with a pair of spaced parallel ears 46, depending from one end thereof and suitably apertured to serve as hinge members, the pawl being thereby pivotally mounted across the inner face of the lower jaw 16, as viewed in the drawing, adjacent its nose end by means of a transverse hinge pin 48 extending through the ears 46, and lower jaw 16, as shown in section in FIGURE 2, the pawl 44 being yieldably biased into upright position by means of a spring 50 mounted on the hinge pin 48 with one of its ends bearing on the underside of the pawl 44, and its opposite end bearing on the bottom of a rectangular clearance recess or cavity 52, formed in the inner face of the lower

jaw 16, whereby the pawl 44 is adapted for limited angular movement between the opposing faces of the jaws 16 toward the fulcrum 14 of the tool 10, from a normal upright position to a substantially horizontal position.

As shown in FIGURES 1, 2, 4 and 6, the convex side of the free end portion of the pawl 44 is suitably abraded, knurled, serrated or the like as at 54, whereby the pawl 44 is adapted to bite or grip the linearly ribbed face of the body portion of the strap S, in response to repeated movement of the jaws 16 toward each other as when drawing a bundling strap S taut.

Further in accordance with the invention and as best shown in FIGURES 2, 4 and 6, movement of the jaws 16 toward each other is limited by a spring biased detent lever 56, pivotally mounted on the straight rear portion of the upper jaw 16, by means of a suitable pivot pin 58. The detent lever 56 comprises a U-shaped end portion in cross-section, wherein one side terminates in a detent finger 60 depending beyond the inner face of the upper jaw 16 into close proximity to the rear inner face 62 of the lower jaw 16, and a finger piece control member 64 extending from its pivoted end portion partly over one of the handle members 12. As shown in FIGURE 2, the detent lever 56 is biased into operative position by means of a small coil spring 66 having one end thereof suitably seated in the upper jaw 16 with its opposite end acting against the under side of its pivotally mounted end portion. Thus, when the jaws 16 are moved toward each other, the detent finger 60 of the detent lever 56, normally in the path of the rear inner face 62 of the lower jaw 16, is brought into engagement therewith as the knife edge 28 on the lip 25 of the lower jaw 16 approaches the slot 40 in the extended free leg 38 of the angle plate 34 on the upper jaw 16, whereby the said knife edge 28 falls short of movement across the slot 40, and precludes a severing operation on a bundling strap S until the free end or trigger 64 of the detent lever 56 is depressed to free the jaws 16 for further movement toward each other as exemplified in FIGURE 6.

In view of the foregoing, when considered in the light of the accompanying drawing, it will be clear that the present invention provides a forged, solid frame hand tool of the pliers type wherein the jaws are off-set or bent at an acute angle to the longitudinal center of said tool and to one side thereof as best seen in FIGURE 8, whereby the insertion of the tail-end of a bundling strap between the nose-end of the jaws, or between said jaws sidewise, will cause the strap to pass to one side of the fulcrum of the tool as it is drawn through the jaws. Moreover, the nose-end of one of said jaws includes an angle plate suitably secured thereto with its free leg extending normal thereto and provided with an open ended transverse slot in one side edge thereof for receiving and guiding a strap between said jaws. The nose-end of the other of said jaws includes an integral, right angular extension terminating in a transverse knife edge having a V-notch centrally thereof for centering a strap thereon, said cutting edge being movable across said open ended slot in shearing relation in response to movement of said jaws toward each other to sever said strap. The invention further provides a pivoted detent means on one of said jaws for automatically limiting movement of said cutting edge short of said open ended slot, to prevent severing said strap while said tool is so held and rotated through an angle of 90 degrees, said detent means being subsequently manually released to permit movement of said cutting edge to cut-off position across said open ended slot upon further movement of said jaws toward each other in response to further movement of the handle members of said tool.

While the invention has been illustrated and described with respect to a preferred embodiment thereof, it is to be expressly understood that various changes and modifications may be made thereon without departing

from the inventive concept underlying the same. Therefore, the invention is not to be limited except as is necessitated by the prior art and the scope of the appended claims.

What is claimed is:

1. A hand tool for tensioning and subsequently cutting a plastic strap when looped about a plurality of bunched articles comprising a pair of jaw members connected for movement toward and away from each other in response to movement of a pair of integral, spring influenced handle members, said jaw members being formed at an acute angle to the longitudinal center line of said tool and to one side of said center line, angular means provided on the nose-end of each of said jaw members disposed normal thereto in opposed relation adapted respectively for supporting and guiding an end portion of a plastic strap between said jaw members and for severing the end portion of said strap upon movement of said angular means to cut-off position upon movement of said jaw members toward each other, and means pivotally mounted on one of said jaw members including a detent normally engaging the other of said jaw members for limiting movement of said jaw members toward each other short of advancing said angular means to cut-off position, said last named means including a manually operable extension for releasing said detent to permit movement of said jaw members to cut-off position.

2. A hand tool for tensioning and subsequently cutting a plastic strap when looped about a plurality of bunched articles comprising a pair of jaw members connected for movement toward and away from each other in response to movement of a pair of integral, spring influenced handle members, said jaw members being formed at an acute angle to the longitudinal center line of said tool and to one side of said center line, angular means provided on the nose-end of each of said jaw members disposed normal thereto in opposed relation adapted respectively for supporting and guiding an end portion of a plastic strap between said jaw members and for severing the end portion of said strap upon movement of said angular means to cut-off position upon movement of said jaw members toward each other, and means pivotally mounted on one of said jaw members including a detent normally engaging the other of said jaw members for limiting movement of said jaw members toward each other short of advancing said angular means to cut-off position, said last named means including a member extending partially over one of said handle members, manually operable for releasing said detent to permit movement of said jaw members to cut-off position.

3. The invention set forth in claim 2 characterized further in that said knife edge is provided centrally of its opposite ends with a V notch whereby to provide clearance for centering an end portion of a plastic strap thereon.

4. A hand tool for tensioning and subsequently cutting a plastic strap when looped about a plurality of bunched articles comprising a pair of jaw members pivotally connected for movement toward and away from each other in response to movement of a pair of integral, spring biased handle members, said jaw members being formed at an acute angle to the longitudinal center line of said tool and to one side thereof, a slotted means mounted on the nose-end of one of said jaw members normal thereto adapted for supporting and guiding an end portion of a strap through said jaw members, the nose-end of the other of said jaw members terminating in a right angular extension in opposed relation and provided with a transverse knife edge movable to cut-off position relative to said slotted means in response to movement of said jaw members toward each other, and a spring biased detent means pivotally mounted on one of said jaw members normally engaging the other of said jaw members for limiting movement of said jaw members toward each other short of advancing said knife

edge into shearing relation with said slotted means, said last named means including a manually operable extension for releasing said detent to permit movement of said knife edge to cut-off position.

5. A hand tool for tensioning and subsequently cutting a plastic strap when looped about a plurality of bunched articles comprising a pair of forged steel jaw members formed at an acute angle relative to the longitudinal center line of said tool and to one side of said center line adapted for movement toward each other in response to movement of a pair of spring influenced handle members normally in spaced apart position, an angle plate mounted on and across the nose-end of one of said jaw members having a transverse open-ended slot in one side edge thereof adapted to guide a tail-end portion of a plastic strap between said jaw members, a cutting member integral with and extending normal to the nose-end of the other of said jaw members movable to cut-off position relative to said open-ended slot in response to movement of said jaw members toward each other, and a spring biased detent lever pivotally mounted on one of said jaw members and normally engaging the other of said jaw members to limit movement of said jaw members toward each other to advance said cutting member short of said open-ended slot, said detent lever including a lever manually operable to release said detent from said one jaw member whereby said jaws are movable toward each other to advance said cutting member to cut-off position across said open-ended slot.

30 6. A hand tool for tensioning and subsequently cutting an end portion of a plastic strap when looped about a plurality of bunched articles comprising a pair of jaw members connected for movement toward and away from each other in response to movement of a pair of integral, spring biased handle members normally in spaced apart position, said jaw members being off-set at an acute angle to the longitudinal center line of said tool and to one side thereof, an angle plate having one leg thereof secured to one of said jaw members with its remaining 35 leg extending across the nose-end thereof at right angles to the opposing faces of said jaw members, the extended leg of said angle plate being provided with a transverse, open ended slot in one side edge thereof adapted to support and guide an end portion of a looped strap between said jaw members, said other jaw member including an integral lip extending at right angles across the nose-end thereof in opposed relation to the extended leg of said angle plate, said integral lip being provided with a transverse knife edge on its free end movable across said open-ended slot in shearing relation therewith in response to movement of said jaw members toward each other, and a spring influenced detent lever pivotally mounted on one of said jaw members normally engaging the other of said jaw members to limit movement of said integral lip short of the open-ended slot 45 in the extended leg of said angle plate, said detent lever including a member extending partially over one of said handle members operable manually to release said detent to permit movement of said knife-edge to cut-off position relative to the open-ended slot in the extended 50 free leg of said angle plate.

7. A hand tool for tensioning and subsequently cutting a plastic strap when looped about a plurality of bunched articles comprising a pair of jaw members formed at an acute angle relative to the longitudinal center line of said tool and disposed to one side of said center line adapted for movement toward each other in response to movement of a pair of integral, spring biased handle members normally in spaced apart position, an angle plate mounted across the nose-end of one of said jaw members having a transverse open-ended slot in one side edge of its extended free leg adapted to guide an end portion of a plastic strap between said jaw members, a spring biased serrated pawl pivotally mounted on the other of said jaw members across its inner face and

adjacent the nose-end thereof operable between said jaw members upon movement thereof toward each other to impart small increments of relative movement to said strap through said jaw members, and a cutting member having a transverse knife edge integral with the nose-end of the other of said jaw members and extending normal thereto in opposed relation to the free leg of said angle plate and movable across the open-ended slot therein in response to movement of said jaw members toward each other to sever a strap end portion, and a 10 spring biased lever including a depending detent member pivotally mounted on one of said jaw members with its depending detent normally engaging the other of said jaw members to limit movement of said cutting member short of said open-ended slot, said lever including a 15

member extending partially over one of said handle members for manually releasing said detent member to permit movement of said cutting member and said open-ended slot in the free leg of said angle plate to cut-off position, said cutting member having a V-notch centrally of its knife-edge adapted for centering a strap end portion thereon.
